PAPER HOLDER

Filed May 26, 1926

FIG. 1 -

FIG. 3.

FIG_2_

FIG. 4.

Inventor
George C. Hume
by Herbert W. J. James
Attorney.

UNITED STATES PATENT OFFICE.

GEORGE C. HUME, OF CHILTON, WISCONSIN.

PAPER HOLDER.

Application filed May 26, 1926. Serial No. 111,765.

This invention relates to portable holders or clips used on desks for holding checks and other similar papers; and it consists in the novel construction and combination of the 5 parts hereinafter fully described and claimed.

In the drawings, Figure 1 is a side view of a paper fastener constructed according to this invention. Fig. 2 is a plan view of the 10 same. Fig. 3 is a front view, and Fig. 4 is a vertical cross-section taken on the line 4-4 in Fig. 1.

A base plate 6 is provided, and has a sheet of soft material 7 on its underside to 15 keep it from scratching the desk or table. An upright 8 projects from the back edge of the base plate, and has a vertical slot 9 in it. A horizontal arm 10 projects forwardly from the top of the upright, over the base 20 plate, and has a longitudinal slot 12 in it. Two arms 14 project forwardly from the side edges of the upright a little below the level of the top arm 10.

An angle-shaped block 15 is pivoted at its 25 upper end portion to a pin 16 extending between the free end portions of the side arms 14. The lower portion of the block 15 has undercut recesses 17 formed in its face, and 30 18 are cylindrical pads of india rubber or similar soft material secured in the recesses, and projecting below the level of the face of the block. A curved rod 20 is secured to the block 15 at one end, and projects upwardly 35 through the slot 12 in the top arm. A curved helical spring 22 is arranged loosely around the curved rod 20 between the block 15 and the top arm 10, and normally presses the lowest pad against the base plate. The 40 rod 20 has a knob 21 at its top.

A clip plate 24 is arranged above the base plate adjacent to the upright, and has an upwardly offset portion 25 at its middle part. A guide 26 has a T-shaped head 45 works in the slot 9 of the upright, and is riveted to the underside of the offset portion 25, so that the clip plate is slidably connected to the upright. A rod 27 is secured to the offset portion 25, and projects through a hole in the top arm 10, and has a knob 28 at its 50 top which bears on the top arm and holds the clip plate a little above the base plate.

A helical spring 29 encircles the rod 27 between the offset portion and the top arm, and presses the clip plate downwardly.

The checks or other papers to be held are 55 slipped under the block 15 when the clip plate is raised a little to receive them, and are then securely held as the angle-shaped form of the block 15 operates like a pawl, and prevents them from being moved 60 easily in the reverse direction. The block 15 is raised by hand to release the papers, and the clip plate can also be raised if necessary.

When a quantity of papers have been inserted in the holder, the lower part or face of the block 15 is raised to a horizontal position, and both pads 18 bear on the papers and assist in holding them. The block 15 is spaced at a sufficient distance from the clip 70 plate to prevent its lower part from striking the clip plate, when raised to hold a large number of papers. The upper end of the curved spring 22 slides against the underside of the top arm when the curved rod 75 is raised and slides along the slot in the top arm.

What I claim is:

1. A paper holder, comprising a base provided with an upright and having also 80 side arms and a slotted top arm which projects from the upright over the base, an angle-shaped block pivoted to the side arms and provided with a lifting rod which projects through the slot in the top arm, a 85 spring which presses the said block downwardly, and a slideable spring-pressed clip plate arranged adjacent to the said upright over the base plate.

2. A paper holder as set forth in claim 1, 90 the lower part of the angle-shaped block being provided with undercut recesses, and pads engaging with the recesses and projecting from the block.

3. A paper holder as set forth in claim 1, 95 the said upright having a vertical slot, and the said clip plate having a guide which is slideable in the said slot.

In testimony whereof I have affixed my signature.

GEORGE C. HUME.
